DISPLAY STAND FOR DISHES AND THE LIKE

Eirvan C. Cantrell, 1801 W. Anaheim St.,
Long Beach, Calif. 90813

Filed Oct. 31, 1968, Ser. No. 14,243

Term of patent 14 years

Int. Cl. D6—01

U.S. Cl. D80—9

FIG.1

I claim:

The ornamental design for a display stand for dishes and the like, as shown and described.
